UNITED STATES PATENT OFFICE.

EDWARD J. RAPPS, OF PHOENIX, ARIZONA.

WASHING MACHINE.

Application filed July 8, 1922. Serial No. 573,568.

To all whom it may concern:

Be it known that I, EDWARD J. RAPPS, a citizen of the United States, residing at Phoenix, in the county of Maricopa and State of Arizona, have invented new and useful Improvements in Washing Machines, of which the following is a specification.

In carrying out the present invention it is my purpose to provide a washing machine whereby clothes, linen, etc., may be thoroughly and effectively washed, and which, after the washing operation, may be used as a wringer, so as to relieve clothes, linen, etc., of the water therein.

It is also my purpose to improve and simplify the general construction of washing machines and to provide a washing machine which will embrace the desired features of simplicity, efficiency and durability; and which may be manufactured and marketed at small cost.

With the above recited objects in view, and others of a like nature, the invention resides in the construction, combination and arrangement of parts set forth in and falling within the scope of the appended claims.

In the accompanying drawings:

Figure 1 is a view in front elevation of a washing machine constructed in accordance with my invention.

Figure 2 is an end view of the same.

Figure 3 is a sectional view on the line 3—3 of Figure 4.

Figure 4 is a sectional view on the line 4—4 of Figure 2.

Figure 5 is a sectional view through the machine showing the same as used for wringing purposes.

Figures 6, 7 and 8 are detailed views of the invention.

Referring now to the drawings in detail, 1—1 designate vertical supports of appropriate construction mounted upon base members 2 and connected together by means of a cross bar 3. On the upper ends of the standards 1—1 are bearings 4—4 respectively.

The receptacle or container of my improved washing machine is indicated as an entire by the reference character 5, and in accordance with my invention this receptacle comprises a lower half or section 6 and an upper half or section 7. The lower section embodies a bottom wall, side and end walls, while the upper section embodies a top wall and side and end walls. The lower edges of the side and end walls of the upper section are formed with a tongue that fits into a groove in the corresponding edges of the side and end walls of the bottom section, 60 as clearly illustrated in Figures 3 and 4 of the drawings, so as to form a fluid tight joint between the sections. The end walls of the bottom section 6 of the receptacle or container adjacent to the upper ends thereof 65 are formed with outwardly extending axially alining trunnions 8 that fit into the bearings 4, so that the container may be supported by the standards 1 and rotated about the trunnions, one of the trunnions being 70 provided with a crank handle 9 by means of which the receptacle may be revolved.

The opposite side walls of the lower section 6 of the receptacle are formed with inclined guideways 10 arranged in pairs, the 75 pairs of guideways on one side wall alining respectively with the guideways on the other side wall. The top side walls of the top section 7 are also equipped with pairs of guideways 11 inclined in a direction reverse 80 to the inclination of the guideways 10 in the bottom section. The pairs of guideways 11 on one side wall of the top section aline respectively with the guideways on the other side wall. Slidably mounted in each pair of 85 alining guideways is a washboard 12 formed with perforations 12' suitably spaced apart, having the opposite faces roughened and the upper edges of the washboards in the lower section terminate flush with the upper 90 edges of the side and end walls of such section, while the lower edges of the washboards in the top section terminate with the side walls of such section and lie in edge to edge contact with the washboards in the 95 bottom section when the two sections are placed together, as clearly shown in Figures 3 and 4 of the drawings. These washboards, spaced apart as just described, form pockets 100 to receive the clothes, linen or other material to be washed, and below the washboards and the guideways in the bottom section is a false bottom 13 perforated as at 14, while at the upper ends of the washboards and guideways in the top section is a false top 15 perforated as at 16. Mounted in each pocket is a trough-like member 17 shown in perspective in Figure 7 of the drawings. These trough-like members open toward the bottom and top walls, respectively, of the sections 6 and 7 of the receptacle and are of less width 110 than the pockets formed by the washboards,

so that as the receptacle is turned the trough-like elements may slide back and forth in the pockets, in order to insure the cleansing of the clothes.

- 5 The top and bottom sections of the container are hinged together upon one side by means of hinges 17^a of appropriate construction and the other side of the receptacle is provided with a keeper 18 on the top section and a latch member 19 on the bottom section, the latch member being engageable with the keeper to hold the sections in receptacle formation, as clearly shown in Figures 1, 2 and 3 of the drawings.
- 10 In practice, the bottom section is filled with soap and water or other washing compound to the desired level and clothes, linen, etc., placed in pockets formed by the washboards. The top section is now swung onto the bottom section and latched thereto and the receptacle as an entirety rotated about the trunnions by means of the handle. In the rotation of the receptacle the washing compound is agitated and the trough-like elements slide with the clothes back and forth within the pockets, while the washing compound thoroughly saturates the contents of the receptacle and passes through the perforated false bottom and false top and also through the perforated washboards, with the result that the clothes or contents of the receptacle are thoroughly cleansed. The washboards are held in their respective guides by means of wedge-like pins 19' that pass through alining openings in the guides in the washboards.
- 15 When it is desired to wring the clothes the water or washing compound is drained from the receptacle and the top section removed, but after the removal of the top section the washboards in the bottom section are also removed and the clothes placed upon the false bottom. The perforated board 20 is then placed upon the clothes to be wrung, as illustrated in Figure 5 of the drawings, and over this perforated board 20 is placed a top member 21 formed centrally with an upstanding fulcrum member 22. Secured to one of the trunnions is one end of a hook element 23 and pivoted to the other end element is one end of a lever 24, the central portion of which rests upon the fulcrum post 22. The other end of the lever 24 is provided with a handle 25 by which pressure may be exerted upon the top member 21 and the board 20, thereby enabling the clothes to be compressed between the board 20 and the false bottom in the lower section, so that the contents of the bottom section may be relieved of the water.

I have entered into a detailed description of the construction and relative arrangement of parts embraced in the present and preferred embodiments of my invention with a view to imparting a full, clear and exact un-

derstanding of the said embodiments. I do not desire, however, to be understood as confining myself to the said specific construction and relative arrangement of parts, inasmuch as in the future practice of my invention such changes or modifications may be made as fairly fall within the scope of my invention as defined by my appended claims.

Having thus described the invention, what is claimed as new, is:—

1. A washing machine comprising a receptacle formed with top and bottom sections, trunnions on the bottom section alining axially with each other, bearings supporting said trunnions whereby said receptacle may be rotated, pairs of guide members secured to the opposite side walls of each section, the pairs on one side wall alining respectively with the pairs of guides on the other side wall, washboards mounted in said guides, the washboards in one section being inclined in a direction reverse to the direction of the washboards in the other section, said washboards defining pockets to receive the clothes to be washed and trough-like elements in said pockets adapted in the rotation of the receptacle to slide within the pockets to facilitate the washing of the clothes.

2. A washing machine comprising a receptacle formed with top and bottom sections, trunnions on the bottom section alining axially with each other, bearings supporting said trunnions whereby said receptacle may be rotated, pairs of guide members secured to the opposite side walls of each section, the pairs on one side wall alining respectively with the pairs of guides on the other side wall, washboards mounted in said guides, the washboards in one section being inclined in a direction reverse to the direction of the washboards in the other section, said washboards defining pockets to receive the clothes to be washed and trough-like elements in said pockets adapted in the rotation of the receptacle to slide within the pockets to facilitate the washing of the clothes, a false bottom in said lower section closing the bottom ends of the pockets and a false top in the upper section closing the upper ends of the pockets, said false bottom and top being perforated, whereby the washing compound may circulate freely in the rotation of the receptacle.

3. A washing machine comprising a receptacle formed with top and bottom sections, trunnions on the bottom section alining axially with each other, bearings supporting said trunnions whereby said receptacle may be rotated, pairs of guide members secured to the opposite side walls of each section, the pairs on one side wall alining respectively with the pairs of guides on the other side wall, washboards mounted in said

guides, the washboards in one section being inclined in a direction reverse to the direction of the washboards in the other section, said washboards defining pockets to receive the clothes to be washed and trough-like elements in said pockets adapted in the rotation of the receptacle to slide within the pockets to facilitate the washing of the clothes, a false bottom in said lower section closing the bottom ends of the pockets and a

false top in the upper section closing the upper ends of the pockets, said false bottom and top being perforated, whereby the washing compound may circulate freely in the rotation of the receptacle, and means carried by said guides to hold said washboards in place. 15

In testimony whereof I affix my signature.

EDWARD J. RAPPS.
